(**) Term: **15 Years**

(57) **CLAIM**

(21) Appl. No.: **29/621,593**

The ornamental design for a case with pocket for electronic device, as shown and described.

(22) Filed: **Oct. 10, 2017**

DESCRIPTION

(51) **LOC (11) Cl.** **14-02**

FIG. 1 is a front perspective view of a case with pocket for electronic device shown in the open position in a first configuration;

(52) **U.S. Cl.**

FIG. 2 is a front elevation view of the FIG. 1 device in the first configuration;

USPC **D14/440**

FIG. 3 is a rear elevation view of the FIG. 1 device in the first configuration;

(58) **Field of Classification Search**

FIG. 4 is a right-side elevation view of the FIG. 1 device in the first configuration;

USPC D14/440; 206/45.23, 320, 45.2;

FIG. 5 is a left-side elevation view of the FIG. 1 device in the first configuration;

361/679.55; 294/25; 224/218

FIG. 6 is a top plan view of the FIG. 1 device in the first configuration;

CPC ... G06F 1/1628; G06F 1/1626; A47B 23/044;

FIG. 7 is a bottom plan view of the FIG. 1 device in the first configuration;

H04B 1/3888; H05K 5/0217

FIG. 8 is a rear perspective view of the FIG. 1 device in the first configuration;

See application file for complete search history.

FIG. 9 is a front perspective view of the FIG. 1 device shown in the open position in a second configuration;

(56) **References Cited**

FIG. 10 is a right-side elevation view of the FIG. 1 device in the second configuration;

U.S. PATENT DOCUMENTS

FIG. 11 is a front perspective view of the FIG. 1 device shown in the open position in a third configuration; and,
